CORRUGATED PLASTIC PANEL

Lloyd N. Faulkner and Suzanne Faulkner, Los Angeles,
Calif., assignors to Vistron Corporation, Cleveland,
Ohio, a corporation of Ohio

Filed Aug. 1, 1968, Ser. No. 12,992

Term of patent 14 years

Int. Cl. D25—01

U.S. Cl. D54—2

FIG. 1

FIG. 2

FIG. 3

FIG. 4

FIG. 5

FIG. 6

FIG. 7

FIG. 8

FIGURE 1 is a perspective view of our preferred novel panel design;

FIGURE 2 is an enlarged fragmentary view;

FIGURE 3 is an elevation of FIGURE 2;

FIGURE 4 is a further enlarged fragmentary view of FIGURE 3;

FIGURE 5 is a view similar to FIGURE 2 showing a modification;

FIGURE 6 is an end elevation of FIGURE 5;

FIGURE 7 is a view similar to FIGURE 5 showing a second modification; and

FIGURE 8 is an end elevation of FIGURE 7.

We claim:

The ornamental design for a corrugated plastic panel, as shown and described.
